UNITED STATES PATENT OFFICE.

WALTER FERRIS AND PETER NORDSTROM, OF MILWAUKEE, AND WERNER LEHMAN, OF SOUTH MILWAUKEE, WISCONSIN, ASSIGNORS TO BUCYRUS COMPANY, OF SOUTH MILWAUKEE, WISCONSIN, A CORPORATION OF WISCONSIN.

ANCHORAGE FOR EXCAVATOR TRACK-LINES.

1,281,323.

Specification of Letters Patent. Patented Oct. 15, 1918.

Application filed April 6, 1917. Serial No. 160,113.

To all whom it may concern:

Be it known that we, WALTER FERRIS and PETER NORDSTROM and WERNER LEHMAN, being citizens of the United States, the first 5 two named residing at Milwaukee, the last named residing at South Milwaukee, in the county of Milwaukee and State of Wisconsin, (whose post-office address is care of Bucyrus Company, South Milwaukee, Wisconsin,) have invented a certain new and useful Improvement in Anchorage for Excavator Track-Lines, of which the following is a specification.

Our invention relates to improvements in 15 anchorage for excavator track lines and is directed more generally to improvements in the controlling and operating mechanism whereby the cable, tracks, dragging mechanism and the like are supported and operated. 20 One of the objects of our invention is to provide means for supporting, manipulating and controlling the cable track along which the excavating member travels and by which it is supported. Another object is to provide 25 an effective assembly, the controlling mechanism for all the parts, the drag line engine and associated parts being all mounted on a track carried car which supports the tower. Other objects of our invention will appear from time to time in 30 the specification.

Our invention is illustrated more or less diagrammatically in the accompanying drawings, wherein—

35 Figure 1 is a side elevation of the tower; and

Fig. 2 is a detailed side elevation of a part of the track line tightening mechanism.

Like parts are indicated by like letters in 40 all the figures.

The track A resting on the cross ties A¹, A¹ carry the usual type of cross trucks A³, A³ which support the car frame A⁴ upon which is a housing A⁵ containing the machinery, driving and operating parts not here shown.

45 The carriage or car frame A⁴ carries a tower made up of the two upright parallel members B, B. These members B, B are tied together at the top by the cross member B¹ and steadied and supported by the diagonal stay or support members B² extending upwardly from the body of the car. The short strut B³ supports the central portion

of the stays B² and also furnishes a foundation for the lower end of the track B⁴, the upper end of which is carried by the stay B².

55 The drag line C¹¹ runs over the sheave C⁹ passing down to the drum D, the driving and controlling mechanism of which is not here shown. The inboard end of the track cable C¹⁰ terminates at the bridle D¹. The cables D², D² pass over a sheave D⁴, D⁵ on the bridle and around a sheave D⁶, to the hoisting drum D⁷ on the frame of the car. The 60 sheave D⁶ supports a cable D⁸. This cable passes over a guide quadrant D⁹ having a series of cable rollers D¹⁰ and is anchored on a piston rod D¹¹ attached to a piston D¹² in the cylinder D¹³. The down side of this 65 cylinder is connected to a steam boiler so that the pressure of the steam in the boiler tends to hold the cylinder and piston in the relative position shown. The compression in the cylinder is such that any tension great 70 enough to tip the tower over will be great enough to overcome the steam pressure and to make the sheave D⁶ travel up. The operator observing this will cease to wind up on the drum D⁷, and thus all danger will be 75 obviated.

The bridle D¹ is supported by a cable E which passes over the block E¹, is guided by the sheave E², passes over the sheave E³ on the counterweight E⁴ and is anchored on the 80 stay B². The counterweight is free to travel along the guide B⁴ and has for its function to support the bridle when the weight of the track cable is insufficient to do so.

We have not illustrated the engine controlling devices and the like specifically because they are of a well-known type and form no part of our invention. It will of course be evident that any suitable type of mechanism to get the desired result will do.

90 It will be evident that while we have shown in our drawings an operative device, still many changes might be made both in size, shape and arrangement of parts without departing from the spirit of our invention and we wish therefore, that our drawings be regarded as in a sense diagrammatic.

100 The use and operation of our invention are as follows:—

The head tower which we have more specifically illustrated travels along the track on the opposed side of the excavation and carries all of the operating machinery.

It will be understood that part of the excavating is done by tightening and loosening the track cable. The windlass shown is provided with a double rope tackle for drawing in or paying out on the track line, but if the power available is likely to be exceedingly large, there is a possibility that the operator may so tension the track line as to tip the tower over.

10 Automatic means are provided to prevent tipping the tower by application of force to the track line. These means take the form of the steam cylinder shown. If the tension in the line becomes great enough to tip the 15 tower over, the cylinder will be operated automatically, the piston pulling down against the pressure of the steam in the cylinder, and the operator will see that the cable is paying out. This will warn him 20 that he is exerting too great a tension in the track line and he will then stop.

The weight of the tackle and the resistance to movement of the rope through the 25 sheave is sometimes very great. Under some circumstances the weight of the track line is not sufficient when it is to be paid out to pull up on the bridle. The counterweight shown has sufficient tension to pull the tackle out 30 against the frictional resistance so that the tightening tackle will not become tangled when the track cable is slack.

We claim:

1. The combination with a track line of means for drawing in on it comprising a 35 winding drum, a cable and a series of sheaves, some of them anchored, others directly attached to the end of the track line, the cable being wound about them and means for releasing the anchored sheave 40 when the tension in the track line exceeds a predetermined amount.

2. The combination with a track line of means for drawing in on it, comprising a 45 winding drum, a cable and a series of sheaves, some of them anchored, others directly attached to the end of the track line, the cable being wound about them and means for releasing the anchored sheave 50 when the tension in the track line exceeds a predetermined amount, said anchorage comprising a cylinder, a piston therein and a connection between it and the sheave.

3. The combination with a track line of means for drawing in on it comprising a 55 winding drum, a cable and a series of sheaves, some of them anchored, others directly attached to the end of the track line, the cable being wound about them and means for releasing the anchored sheave 60 when the tension in the track line exceeds a predetermined amount, said anchorage comprising a cylinder, a piston therein, a connection between it and the sheave, an indicating quadrant, a series of rollers mounted 65 on the quadrant, the cable being guided

by said rollers between the sheaves and the piston.

4. The combination of a track line of means for drawing in on it comprising a winding drum, a cable and a series of 70 sheaves, some of them anchored, others directly attached to the end of the track line, the cable being wound about them and means for moving the anchored sheave forwardly when the tension in the track line 75 exceeds a predetermined amount.

5. The combination of a track line of means for drawing in on it, comprising a winding drum, a cable and a series of 80 sheaves, some of them anchored, others directly attached to the end of the track line, the cable being wound about them and means for releasing the anchored sheave when the tension in the drag line exceeds a 85 predetermined amount, said anchorage comprising a cylinder, a piston therein and a connection between it and the sheave.

6. The combination of a track line of means for drawing in on it comprising a winding drum, a cable and a series of 90 sheaves, some of them anchored, others directly attached to the end of the track line, the cable being wound about them and means for releasing the anchored sheave when the tension in the track line exceeds 95 a predetermined amount, said anchorage comprising a cylinder, a piston therein, a connection between it and the sheave, a quadrant, a series of rollers mounted on the quadrant, the cable being guided by said rollers 100 between the sheaves and the piston.

7. The combination with an excavating tower and a track line of a sheave over which the track line passes a bridle to which the inner end of the track line is fastened, 105 sheaves mounted thereon, other sheaves separately mounted in a separate, loosely suspended bridle, a cable wound about the sheaves and anchored on one of them, means for drawing in on the cable and separate 110 means for releasing tension on the sheaves.

8. The combination with an excavating tower and a track line of a sheave over which the track line passes, a bridle to which the inner end of the track line is fastened, 115 sheaves mounted thereon, other sheaves separately mounted in a separate, loosely suspended bridle, a cable wound about the sheaves and anchored on one of them, means for drawing in on the cable and separate 120 means for releasing tension on the sheaves consisting of a cylinder a piston operating therein, direct connection between the cylinder and the sheaves, and means for maintaining pressure against the piston. 125

9. In an excavator tower the combination of a track line a bridle suspended on the end thereof, sheaves mounted on the bridle, sheaves separately mounted below the bridle, with means for drawing the sheaves together 130

and separate automatic means for releasing tension on the sheaves.

10. In an excavator tower the combination of a track line of a bridle suspended on the end thereof sheaves mounted on the bridle, sheaves separately mounted below the bridle, an anchored cable wound about the sheaves and means for exerting tension thereon to draw the two sets of sheaves together.
- 10 11. In an excavator tower the combination of a track line of a bridle suspended on the end thereof sheaves mounted on the bridle, sheaves separately mounted below the bridle, an anchored cable wound about the 15 sheaves and means for exerting tension thereon to draw the two sets of sheaves together and means for releasing tension consisting of a cylinder, a piston operating therein, direct connection between piston and 20 sheaves and means for maintaining pressure against the piston.
12. In an excavator tower the combination of a track line, a bridle suspended on the end thereof, sheaves mounted on the bridle, 25 sheaves separately mounted below the bridle, with means for drawing the two sets of sheaves together and separate means for supporting the bridle when the tension on the track line is reduced.
- 30 13. The combination with a track line of means for drawing in on it, comprising a winding drum, a cable and a series of

sheaves, some of them anchored, others attached to the end of the track line, the cable being wound about them, and means for releasing the anchored sheaves when the tension in the track line exceeds a predetermined amount, said means comprising a cylinder, a piston therein and a connection between it and the sheaves consisting of a 35 cable attached thereto.

14. In an excavator tower the combination of a track line, a bridle suspended on the end thereof, sheaves mounted on the bridle, sheaves separately mounted below 40 the bridle, with means for drawing the sheaves together and separate means for supporting the bridle when the tension on the track line is reduced consisting of a cable attached thereto, a sheave over which 45 it is led, a weight suspended on the cable and a track on which the weight slides.

Signed at South Milwaukee, Wisconsin,
